UNITED STATES PATENT OFFICE.

EDWARD C. OSBORN AND HERBERT OSBORN, OF BROOKLYN, NEW YORK.

DESIGN FOR A PAPER BOX.

SPECIFICATION forming part of Design No. 16,831, dated August 3, 1886.

Application filed May 10, 1886. Serial No. 261,753. Term of patent 7 years.

To all whom it may concern:

Be it known that we, EDWARD C. OSBORN and HERBERT OSBORN, both of the city of Brooklyn, in the county of Kings and State of New York, have invented a new and original Design for a Paper Box, of which the following is a specification, reference being had to the accompanying drawings, in which—

Figure 1 is a perspective view of a box embodying our design, giving a general view of the design, but on too small a scale to represent the details of ornamentation, which are represented in the following figures, viz: Figs. 2, 3, and 4, which represent, respectively, three sides of the box, and Fig. 5, which represents the top of the box.

Similar letters of reference designate corresponding parts in the several figures.

The box is of parallelopipedal and nearly cubical form. The two longer sides A, A, one of which is shown in Figs. 1 and 4, have each running down it from top to bottom two upright and parallel double stripes, b b, at about equal distances from its ends. Of the shorter sides, 20 the one B, which is concealed from view in Fig. 1, but shown in Fig. 3, has running down its mid-length an upright double stripe, b. The other one, C, of the shorter sides has running round it parallel with and near its edges 25 an ornamental border, c, in the Greek style, and within this border it has three outline ornaments—viz., one, d, in the form of a double arch, with inwardly-turned and reversed scroll-like ends; the second, e, is of lozenge form, and 30 the third, f, is in the form of an oblong parallel-sided figure, with salient triangular ends.

The top D of the box has running centrally along its greater length a somewhat irregular

double stripe, h, and has also running across it at about equal distances from its ends two 40 parallel double stripes, b b, and at and near the intersections of the stripes there are representations of knots, i i.

Those portions of the surfaces of the several sides A B C and top D not occupied by the 45 stripes and ornaments hereinabove described are covered by a peculiar style of zigzag line ornamentation, j j, the nature of which can better be understood by reference to Figs. 2, 3, 4, and 5 than by any description of it. The 50 spaces between the lines of this ornamentation are shaded in some parts between the lines and left plain in other parts, in order to render more apparent the peculiar combination of zigzag lines.

What we claim as our invention, and desire to secure by Letters Patent, is—

1. The design for a paper box, consisting of stripes b b and the zigzag ornamentation j j, substantially as herein represented and described.

2. The design for a paper box, consisting of the stripes b, the border c, the line ornamentation d e f, and the zigzag ornamentation j, the whole arranged substantially as herein represented and described.

3. The design for a paper box, consisting of the intersecting stripes b b, the knots i i at the intersection of said stripes, and the zigzag ornamentation j, all substantially as herein represented and described.

EDWARD C. OSBORN.
HERBERT OSBORN.
